UNITED STATES PATENT OFFICE.

JENNIE GRIFFIN STICKNEY, OF SAN FRANCISCO, CALIFORNIA.

DESIGN FOR PLAYING-CARDS.

59,527.

Specification for Design.

Patented Oct. 25, 1921.

Application filed September 8, 1920. Serial No. 409,003. Term of patent 7 years.

To all whom it may concern:

Be it known that I, JENNIE GRIFFIN STICKNEY, a citizen of the United States, residing at 972 Bush street, in the city and county of San Francisco, State of California, have invented a new, original, and ornamental Design for Playing-Cards, of which the following is a specification, reference being had

to the accompanying drawing, forming part thereof.

The drawing is a plan view of a deck of playing cards showing my new design.

I claim:

The ornamental design for playing cards, as shown.

JENNIE GRIFFIN STICKNEY.
